UNITED STATES PATENT OFFICE.

EDWIN F. WANOUS, OF MINNEAPOLIS, MINNESOTA.

DOOR-CATCH.

1,381,372.

Specification of Letters Patent. Patented June 14, 1921.

Application filed August 19, 1920. Serial No. 404,615.

To all whom it may concern:

Be it known that I, EDWIN F. WANOUS, a citizen of the United States, residing at Minneapolis, in the county of Hennepin and 5 State of Minnesota, have invented certain new and useful Improvements in Door-Catches; and I do hereby declare the following to be a full, clear, and exact description of the invention, such as will enable others 10 skilled in the art to which it appertains to make and use the same.

My invention has for its object to provide an extremely simple and highly efficient low cost door catch adapted for application to 15 many different kinds of doors, but especially adapted for use on large garage doors; and to the above ends, generally stated, the invention consists of the novel construction and combination of parts hereinafter de- 20 scribed and defined in the claims.

The device comprises two main elements, to wit, a pin supporting bracket and a catch pin pivoted or loosely jointed thereto at one end. When the bracket is properly applied 25 to a door the free end of the pin will swing down into engagement with the ground, concrete base or floor, and will hold the door in open position. The pin supporting bracket is provided with a projecting lug 30 or arm having a notch in which the free end portion of the pin may be placed when it is desired to throw the catch device out of action.

The invention is illustrated in the accompanying drawings wherein like characters 35 indicate like parts throughout the several views.

Referring to the drawings:

Figure 1 is a front elevation showing a 40 garage and showing my improved door catch applied to doors thereof, one of the doors being closed with the catch device in an inoperative position and the other door being swung open and with the door catch in an 45 operative position;

Fig. 2 is an enlarged section taken on the line 2-2 of Fig. 1;

Fig. 3 is a perspective view of the door catch removed from the door; and

50 Fig. 4 is a fragmentary view partly in elevation and partly in section, showing a detachable pin cap applied to the end of the pin.

The numeral 1 indicates a garage having 55 the customary swinging or hinged doors 2.

The door catch, as preferably constructed,

comprises a pin supporting bracket made from a flat steel or iron bar 3 provided with out-turned ends affording ears or lugs 4 and 5. The ear 4 is perforated and the looped end of a strong iron or wood catch pin 6 is pivoted or loosely jointed thereto. The ear 5, on its upper edge, is provided with a notch 7 in which the free end portion of the pin 6 may be rested when it is desired 65 to secure the pin out of action.

The bracket 3 is adapted to be secured to the door in proper position by screws 8, or the like, passed through perforations 9 in said bracket.

The bracket should be so applied that when the catch pin 6 is dropped down, it will engage the ground, concrete base, or floor, while standing obliquely to a perpendicular, but at the proper angle to afford 70 a base preventing closing movements of the door. For engagement with the ground, the free end of the pin 6 may be pointed, but for engagement with wooden floors, or especially with concrete bases, a rubber cap 10 75 may be frictionally telescoped onto the end of said pin. This rubber cap will not slip on a wooden floor or a concrete floor base, and moreover, will not mar a wooden floor, and much less a concrete base.

The door catch need not be made in rights and lefts, because it will be operated on a door swinging in either direction, but, as shown, it should be applied a little nearer to the free edge of the right hand door than 80 to the left hand door.

Obviously, the door catch described is of 85 small cost, it may be quickly and easily applied to doors and will be found efficient for the purposes had in view.

What I claim is:

1. A door catch comprising a bracket and a catch pin swiveled thereon, said bracket having an outstanding lug with a seat in which the free end portion of said pin is 100 adapted to rest to hold the same out of action.

2. The combination with a swinging door, of a door catch applied thereto, said door catch comprising a pin supporting bracket 105 having outwardly projecting ends, a catch pin loosely jointed to one out-turned end of said bracket, the other out-turned end of said bracket having a notch to receive the free end portion of said pin to hold the same 110 out of action, and said bracket being applied to the door in such position that said pin,

when dropped down, will engage the ground obliquely.

3. A ¹ or catch comprising a bracket and a catch pin swivelly connected thereto, said bracket having an outstanding lug at one side of the connected end of said pin with a seat, the free end portion of said pin being

adapted to swing laterally and disposed in said seat to hold the same out of action, and a cap telescoped onto the end of said catch ¹⁰ pin.

In testimony whereof I affix my signature.

EDWIN F. WANOUS.
